UNITED STATES PATENT OFFICE

GEORGE FOSTER REZNOR, OF MERCER, PENNSYLVANIA

GAS-HEATED HOT-AIR FURNACE

Application filed October 16, 1928. Serial No. 312,756.

My invention relates to gas-heated hot-air furnaces of the radiator type and is a continuation in part of my application Serial Number 148,672, filed November 16, 1926.

One object of this invention is to provide for a gas-heated hot-air furnace an integral structure or unit of the radiator type in which combustion takes place and in which the burning and waste gases travel to a suitable waste-pipe connection. In practice one or more of my units are assembled in a jacket through which air travels and in which it is heated by the said unit or units, the heated air then passing to one or more rooms for heating them.

Important objects of this invention pertain to the radiator-like construction of the unit and to the integral character of the unit which is cast in one piece and to the shape of the cross-section of the flues connecting the combustion and vent chambers. Other objects appear hereinafter.

Referring to the accompanying drawings, Fig. 1 is a side view of one of the heating units shown in my said application; Fig. 2, a central vertical section of Fig. 1; Fig. 3, an end view of three units on a single base, parts of the units being broken away; Fig. 4, a horizontal section of Fig. 1 on the line 4—4; Fig. 5, a combined front elevation and central vertical section of a modified unit; Fig. 6, an end elevation of Fig. 5, a part being broken away; and Fig. 7, a horizontal section of Fig. 5 on the line 7—7.

Referring first to Figs. 1 to 4, 10 designates one of my heating units intended to be enclosed in a jacket through which air to be heated is passed. Such jackets are old and one is shown in my said application in combination with some of my said heating units, and form no part of the present invention. In fact my heating unit could be used without a jacket if desired.

The unit 10 is cast in one piece and rests on suitable supports, as 11. It comprises the lower or combustion chamber 12, the upper or vent chamber 13 and the flues 14 connecting the chambers. The combustion chamber is shown to be oblong in cross-section with rounded upper and lower portions and the

vent chamber is shown to be rectangular in cross-section. The flues 14, as shown in Fig. 3, are wider than the chambers 12 and 13, that is, the width of the flues is greater than the horizontal transverse dimensions of the chambers. The flues are extended vertically downwardly along the sides of the chamber 12 and beneath the same in the form of hollow ribs 15, the ribs for each chamber 12 being continuous from one side and around the bottom and to the other side. The flues 14 are extended vertically up along the sides of the chamber 13 in the form of hollow ribs 16. Thus, the unit 10 presents a corrugated appearance.

The chamber 12 has a number of external fins 17 surrounding it between consecutive flues 14.

The chamber 13 has the flat metal choke plate 18 lying on the bottom of the chamber to prevent the too free or rapid escape of the hot gases into the vent chamber 13 until most of the heat has been given up through the part of the unit below.

The chamber 12 contains the gas burner 19, and has at one end the flange 20 to which a door, not shown, may be attached in any suitable manner. At the other end of the chamber 12 is the flange 22 to which a cover, not shown, may be applied in any suitable manner. The chamber 13 has its front opening for a door, not shown. The rear of the chamber 13 has the flange 25 which is left open for connection to an off-take pipe to a chimney or the like.

Both the chambers 12 and 13 are corrugated so that expansion and contraction of the chambers is taken care of merely by changes in the spacing of the corrugations. This corrugated construction is very advantageous in a heating unit cast in one piece. This construction is of material value in making the one-piece casting practical because it withstands both the cooling strains in the foundry and the operating strains in practical use. Such construction is particularly useful with the present day full-on and dead-off automatic thermostatic control systems under which such constructions may have the fire out sufficiently long to become quite cool, fol-

lowed by the instantaneous turning on of the gas at maximum rate. Such corrugated one-piece heating units have no joints for escape of burned gases.

5 Fig. 3 shows three units 10 arranged side by side tied together by the tie-bar 26 and resting on the base or support 11.

In Figs. 5, 6 and 7, I show a heating unit which is substantially like that shown in Figs. 10 1, 2, 3 and 4, except that the flues which connect the combustion and vent chambers are divided. The same reference characters will be used as have been used on Figs. 1 to 4 for like parts. Parts in Figs. 5 to 7 which are analogous to parts in Figs. 1 to 4 but differing somewhat therefrom bear the same reference characters as accompany Figs. 1 to 4 but provided with a prime mark.

In Figs. 5 to 7, the flues connecting the 20 chambers 12 and 13 are divided by the space 27 which provides two flues 14' connecting each rib or corrugation 15 to corresponding pairs of ribs 16. The two flues 14' are an improvement over the individual flues 14 for the 25 three reasons following: first, they divide the ascending hot gases into smaller streams with less cross-area as compared with the flue circumference, thus increasing the efficiency of heat transfer to the surrounding air and reducing the size of the stream of hot gas which 30 does not touch the flue walls; second, they greatly favor the molding or casting of the unit in one piece by doing away with the wide and thin one-piece sand core which is 35 required for the one-piece flue which is difficult to manage; and, third, they split up the air in external contact with the unit by providing a front to back air passage between the members of the divided flue.

40 As the casting of a unit is necessarily molded on the side, the casting in one piece which is of considerable size is made more practical by the use of the two sand cores for the double flue 14' instead of one core for the single flue 45 14. The opening 27 between the members of the double flue 14' reduces the depth of the pattern necessary to draw from the sand.

The cross-section of each member of a flue 50 14' is somewhat triangular. Each member is thinner at the wall next to the space 27. This facilitates the drawing from the sand, and the said shape of cross-section of the flue members is equivalent to a large degree of draft which allows the surfaces of the flues 55 14' to come free from the sand mold readily.

I provide the sides of the flues 14' with small ribs or fins 28 to facilitate the transfer of heat from the flues to the surrounding air.

It is to be noted that the space 27 does not 60 reach either the chamber 12 or the chamber 13 whereby the corrugation 15' is extended over the top of the chamber 12, and the corrugations 16' are extended beneath the chamber 13, as clearly shown in Fig. 5. These extensions provide greater relief of expansion and

contraction and strengthen the unit at the points where the flues join the chambers 12 and 13.

I do not desire to be restricted to the precise structure shown and described as many changes may be made within the scope of the appended claims.

I claim—

1. A gas-heated hot-air heating unit cast in a single piece, comprising a combustion chamber, a vent chamber arranged above the combustion chamber and having an opening for waste gases, and flues connecting the chambers, the width of the flues being greater than the width of each chamber and forming transverse corrugations on the sides of the chambers.

2. A gas-heated hot-air heating unit cast in a single piece, comprising a combustion chamber, a vent chamber arranged above the combustion chamber and having an opening for waste gases, there being hollow corresponding corrugations projecting laterally from the chambers, and flues connecting the corresponding corrugations on the two chambers.

3. A gas-heated hot-air heating unit cast in a single piece, comprising a combustion chamber, a vent chamber arranged above the combustion chamber and having an opening for waste gases, there being hollow corresponding corrugations projecting laterally from the chambers, and flues connecting the corresponding corrugations on the two chambers, the corrugations on the sides of the combustion chamber being continued around the bottom thereof.

4. A gas-heated hot-air heating unit cast in a single piece, comprising a combustion chamber, a vent chamber arranged above the combustion chamber and having an opening for waste gases, and flues connecting the chambers, the width of the flues being greater than the width of each chamber and forming transverse corrugations on the sides of the chambers, each flue being divided into two vertical members.

5. A gas-heated hot-air heating unit cast in a single piece, comprising a combustion chamber, a vent chamber arranged above the combustion chamber and having an opening for waste gases, and flues connecting the chambers, the width of the flues being greater than the width of each chamber and forming transverse corrugations on the sides of the chambers, each flue being divided into two vertical members separated to provide a space whereby air to be heated may contact with the opposing faces of the two members.

6. A gas-heated hot-air heating unit cast in a single piece, comprising a combustion chamber, a vent chamber arranged above the combustion chamber and having an opening for waste gases, and flues connecting the chambers, the width of the flues being greater

than the width of each chamber and forming transverse corrugations on the sides of the chambers, each flue being divided into two vertical members, the cross section of the members converging away from each other.

5 7. A gas-heated hot-air heating unit cast in a single piece, comprising a combustion chamber, a vent chamber arranged above the combustion chamber and having an opening for waste gases, and flues connecting the chambers, the width of the flues being greater than the width of each chamber and forming transverse corrugations on the sides of the chambers, each flue being divided along the intermediate portion thereof to form two flue members, each flue being undivided adjacent to the two chambers and forming corrugations continuous with those on the chambers.

10 In testimony whereof I hereunto affix my
15 signature.
